HARRY SIROT, OF NEW YORK, AND HYMAN SIROT, OF BROOKLYN, NEW YORK.

COLLAR BUTTON.

Application filed November 21, 1922. Serial No. 602,367.

To all whom it may concern.

Be it known that we, HARRY SIROT and HYMAN SIROT, citizens of the United States, and residents of the Bronx and Brooklyn, respectively, in the counties of the Bronx and Kings, respectively, and State of New York, have invented certain new and useful Improvements in Collar Buttons, of which the following is a specification.

10 This invention relates to improvements in collar buttons and the main object is to provide a collar button comprising two members which can be secured in place on the collar band of a shirt before it is donned and are further readily interlocked when the shirt is put on.

Another object is to provide a collar button as mentioned which is provided with flanges to retain the button in place on the collar band, said flanges having a means thereon whereby they may be partly opened to admit the insertion of the collar band.

These and other objects will become apparent in the description below, in which characters of reference refer to like-named parts in the drawing.

Referring briefly to drawing, Figure 1 is an elevational view of the component parts of the button separated from each other.

30 Figure 2 is a similar view with the members in interlocked position.

Figure 3 is an end elevational view of Figure 1.

35 Figure 4 is a similar view showing the flange opened.

Figure 5 is a sectional elevational view of the outer flange taken on line 5—5 of Figure 6.

40 Figure 6 is a side elevational view of Figure 5.

Describing the drawing in detail, the numerals 10 and 10^a represent a pair of annular flanges which are separated by a gap 11 within which the collar band of a shirt is received.

Said flanges are aligned and parallel to each other, and are separated by a post 12 which has its periphery concavely rounded. A stud 13 projects from the face of the flange 10^a and has a spherical head 14 thereon for locking the described member with a similar member which has a basket 15 projecting from its inner flange 15^a. Said basket is annular in shape and has a plurality of segments 16 which are separated

55 by slits 17. The spherical socket in the bas-

ket snugly receives the head 14 of the opposite member.

The flanges of each member are preferably spaced to permit occupancy of one end of a collar band, and are also of a diameter 60 slightly greater than the width of a button hole. By having these flanges larger than the button hole it becomes necessary to provide means whereby the button flange may be slipped thru the button hole. This is 65 accomplished by making the outer flanges 10 and 15, respectively, of both members sectional. Said flanges are cut over a quadrant, and the portion of the flange opposite the cut out is solidly formed as indicated by the 70 numeral 18 but has a radially disposed recess 19 formed therein which receives the edge of the revoluble door 20, the latter being centrally pivoted within the flange ears 21 and on the pin 22. A radial pocket 24 75 slidably receives the door and has a flexible spring 25 housed therein which is bent intermediate of its length, one end thereof contacting with the wall 26 of the pocket, the opposite end contacting with the edge of 80 the door and urging the latter in closed position. A depression 23 formed on the face of the door receives a finger nail and telescopes the door into the flange.

This type of collar button permits its being 85 mounted in place before the shirt has been donned. In order to insert the collar band into place between the two flanges, the door 19 is opened as previously described. The noses of the solid portion 18 of the outer 90 flanges are inserted into the button hole. The entire member is then rotated until the outer flange has been transposed thru the button hole to the opposite side of the band. When both members have been mounted to 95 their respective ends of the collar band, both members may be interlocked by pushing the member having the basket over the spherical head 14 of the other member.

We claim:

1. A device of the class described comprising a pair of interlocking members, each member having a pair of spaced apart flanges thereon, the outer flange of each member having a quadrant cut out, said cut out quadrant being adapted to enter and slip helically thru a bottom hole, means for closing said cut out portion, and means for interlocking both members.

2. A device of the class described compris-

- ing a pair of interlocking members adapted to be secured to the shirt collar band, a pair of spaced apart flanges and each member adapted to receive a collar band therebetween, the outer flange of each member having an annular pocket therein, a centrally pivoted door member in each outer flange, said door when telescoped into the flange adapted to permit the insertion into a button hole of smaller dimension than the diameter of the flange, a spring member in said pocket urging said door into closed position, and means for interlocking both members.
10. 3. A device of the class described comprising a pair of interlocking members adapted to be secured to a collar band, a pair of spaced apart flanges on each member adapted to receive a collar band therebetween, the outer flange of each member having an annular pocket therein, a centrally pivoted door member in each outer flange, said door when telescoped into the flange adapted to permit the insertion into a button hole of smaller dimension than the diameter of the flange, a spring member in said pocket urging said door into closed position, and means for interlocking both members.

Signed at New York, in the county of New York and State of New York, this 9th day of November, A. D. 1922.

HARRY SIROT.
HYMAN SIROT.
